US00D552992S

(12) **United States Design Patent** (10) Patent No.: **US D552,992 S**
Spencer (45) Date of Patent: **** Oct. 16, 2007**

(54) **CAP**

(75) Inventor: **Gary Spencer**, London (GB)

(73) Assignee: **Glaxo Group Limited**, Middlesex (GB)

(**) Term: **14 Years**

(21) Appl. No.: **29/239,862**

(22) Filed: **Oct. 5, 2005**

(30) **Foreign Application Priority Data**

Apr. 7, 2005 (GB) 3020860

(51) **LOC (8) Cl.** **09-07**

(52) **U.S. Cl.** **D9/454**

(58) **Field of Classification Search** D9/529,
D9/504, 454, 452, 451, 445, 439, 438, 435;
D24/224, 221; 220/288, 214; 215/901,
215/252

See application file for complete search history.
